EGG SEPARATOR

Robert D. Parry, 1336 Custer Ave., Cincinnati, Ohio

Filed Nov. 26, 1962, Ser. No. 72,609

Term of patent 14 years

(Cl. D44—29)

I claim:

The ornamental design for an egg separator, substantially as shown.
